UNITED STATES PATENT OFFICE.

JOSEPH S. JENSON, OF NORSE, TEXAS.

GATE.

1,322,190.

Specification of Letters Patent.

Patented Nov. 18, 1919.

Application filed July 8, 1919. Serial No. 309,266.

To all whom it may concern:

Be it known that I, JOSEPH S. JENSON, a citizen of the United States, residing at Norse, in the county of Bosque and State 5 of Texas, have invented certain new and useful Improvements in Gates, of which the following is a specification.

My invention relates to improvements in gates.

- 10 An important object of the invention is to provide a gate which is operated for opening and closing the same, in a positive manner, by pull elements arranged upon opposite sides thereof, the closing movement 15 of the gate not being dependent upon the action of gravity upon the gate, whereby such gate may be constructed light, which will in turn enable the gate to be operated easily and prolong the life of the same.
- 20 In accordance with my invention I provide a gate element which is pivotally connected with the post to swing horizontally, and a pivoted lever arranged to first slightly elevate the free end of the gate, to release 25 the latch, the lever then being free to swing the gate to the open position. The gate is locked in the open position, and to close the same the lever initially slightly elevates the free end of the gate, then lowers the 30 same and swings the gate to the closed position. The opening and closing movement of the gate element are both effected by the movement of the lever.

In the accompanying drawings, forming 35 a part of this specification, and in which like numerals are employed to designate like parts throughout the same,

Figure 1 is a perspective view of a gate embodying my invention,

40 Fig. 2 is a perspective view of a latch device, and,

Fig. 3 is a plan view of a hinge or pivot for the gate.

In the drawings, wherein for the purpose of illustration is shown a preferred embodiment of my invention, the numeral 5 designates a gate element, as a whole, which may be constructed of longitudinal beams 6, connected at their ends with vertical beams 45 7. The gate element may further comprise diagonal beams 8 and horizontal strips 9.

Arranged near one end of the gate element 5 is a post 10, having a hinge element

or L-shaped bracket 11, secured to the lower 55 portion thereof and receiving a co-acting hinged element or eye 13 thereon. These elements constitute a hinge, which will permit the gate element 5 being swung horizontally and also slightly vertically, the element 60 12 being attached to the vertical bar 7.

A vertical bolt or pivot element 13 is rigidly secured to the upper end of the post 10, and has a loose pivotal connection with a 65 lever 14, which is adapted to swing horizontally and vertically within limits. The lever 14 is provided with a strap 15, rigidly secured thereto inwardly of the pivot 13, and this strap has an elongated opening 16, 70 receiving a vertical bolt 17, which is rigidly attached to the top of the beam 7. The elongated opening 16 permits of the gate being swung slightly vertically, as well as horizontally. A flexible element or chain 75 18 is secured to the inner end of the lever 14 and to the upper beam 6, at a point near its center.

The lever 14 is swung in opposite directions by a cable or flexible element 19, secured to the outer end thereof and the opposite ends of this flexible pull element are passed through guides 20 attached to horizontal bars 21, secured to posts 22, arranged 80 upon opposite sides of the gate element. 85

Disposed near the opposite end of the gate element 5, when in the closed position, is a latch device, embodying a supporting strip 23, rigidly secured to the post 24. The upper end of this strip is offset and spaced 90 horizontal strips 25 are rigidly secured thereto. Latches 26 are arranged between the strips 25, and are pivoted thereto at 26, these latches being adapted to contact with a U-shaped stop 27, rigidly secured to the 95 support strip 23. The latches 26 are arranged beneath an inverted V-shaped stop 28, rigidly secured to the post 24. A horizontal keeper or bolt 29 is rigidly secured to the free end of the gate element, and is 100 adapted to contact with the upper ends of the latches 26, swinging the same inwardly, whereby the keeper will be held within and between these latches.

The numeral 30 designates posts arranged 105 near the posts 22, and each post 30 carries a horizontal strip 31 to which is pivoted a latch 32, extending above the same and pro-

vided at its lower end with a lateral extension 33, arranged to contact with the post.

The operation of the gate is as follows:

When the gate element is closed, the operator pulls either end of the flexible element 19, which tends to swing the lever 14 horizontally, as the gate element is now locked in the closed position. This movement of the lever 14 pulls upon the chain 18, which in turn will elevate the free end of the gate element 5, sufficiently, whereby the keeper 29 may pass over the upper end of either latch 26. Further swinging movement of the lever 14 will swing the gate element 5 to the open position and it will be locked in this open position by the keeper 29, engaging behind the latch 32. To close the gate, the opposite end of the flexible element 19 is pulled, to elevate the free end of the gate element, so that the keeper will clear the latch element 32, the gate element being then closed by a continued pulling upon the element 19.

It is to be understood that the form of my invention herewith shown and described, is to be taken as a preferred example of the same, and that various changes in the shape, size, and arrangement of parts may be re-

sorted to without departing from the spirit of my invention, or the scope of the subjoined claim.

Having thus described my invention, I claim:

A gate element provided at one end with a substantially vertical beam, a substantially vertical post arranged near the beam, a hinge connecting the lower end of the beam and the lower portion of the post and adapted to allow the gate element to swing horizontally and to partake of slight vertical swinging movements, a substantially horizontal operating lever pivotally connected with the upper end of the post, a strap secured to one end portion of the lever and forming an elongated socket, a pivot element secured to the upper end of the beam and pivotally mounted within the elongated socket and adapted to slide longitudinally therein, and a flexible non-extensible element secured to the inner end of the lever and connected with the gate element inwardly of the pivot element, and means to move the lever.

In testimony whereof I affix my signature.

JOSEPH S. JENSON.
